HIS ATTORNEY

UNITED STATES PATENT OFFICE.

JEROME TRAVIS, OF TOLEDO, OHIO.

GAS BURNER.

Application filed May 10, 1922. Serial No. 559,745.

To all whom it may concern:

Be it known that I, JEROME TRAVIS, a citizen of the United States, residing at Toledo, in the county of Lucas and State of Ohio, have invented new and useful Improvements in Gas Burners, of which the following is a specification.

My invention relates to gas burners for burning natural or artificial gas, and designed for use in heating furnaces, stoves, ranges, and in other situations.

An object of the invention is to provide a highly efficient burner of the character indicated with which complete combustion is obtained, which is of simple construction, inexpensive to manufacture, durable, reliable, compact and which may be readily assembled with any desired number of like units.

20 A feature of the invention consists in the provision of a burner which is entirely free from the "back firing" or jumping of the flame back into the mixing chamber, which so frequently happens in burners in common use. In my burner there is no mixture of air with the gas before it issues, so that the jumping back of the flame is impossible. Moreover, the burner furnishes its own pilot flame and continues to burn until 25 the supply of gas is completely cut off, thereby avoiding the danger of becoming extinguished when the gas pressure is low and allowing the gas to escape without burning.

30 Other objects of the invention and the precise nature thereof will appear herein-after.

In the accompanying drawings, which illustrate a burner constructed in accordance 40 with the principles of my invention,—

Figure 1 is a plan view of the burner.

Figure 2 is an end elevation.

Figure 3 is a longitudinal sectional elevation at the line III—III on Figure 1, and 45 a portion being broken away.

Figure 4 is a section at the line IV—IV on Fig. 1.

Figure 5 is a horizontal section of a portion of the expansion chamber, as indicated 50 by the arrows V—V on Figure 4.

Figure 6 is a diagrammatic view showing a group of burners.

Figure 7 is a similar view of a modified arrangement of the burners.

55 The burner as herein shown, comprises a hollow body A providing an expansion

chamber in which the gas is heated and expanded before it issues for burning, and a baffle B. The body A is preferably cast in a single piece and forms the expansion 60 chamber 10 which is substantially cylindrical and is provided at its under side with a number of hollow transverse arms or pockets 11. The gas is admitted to the burner through a pipe 12, and issues therefrom 65 through small apertures 13 formed in the upper walls of the compartments 11.

The baffle B comprises inclined baffle plates or walls 14 extending lengthwise of the burner, and integral ends 15. The baffle seats on 70 arms 16 formed on the ends of the body A and which extend laterally therefrom, the inclined walls 14 bearing against the inclined ends of said arms. The parts A and B are locked together by the pipe 12 75 and by a plug 17 which closes the end of the expansion chamber.

In operation, the gas which enters the expansion chamber is highly heated and expanded before it issues from the apertures 13. The pencils of gas escaping from these apertures, strike the inclined baffle walls 14 and are thereby spread or dissipated and mixed with the air at or near the initial burning point. This burning 80 point is so closely held to the expansion chamber that the latter is highly heated and the gas thereby raised to a high temperature before it issues. The flames thus produced on the opposite sides of the expansion chamber, by the natural upward movement of the heated column of air and gas ascending between the baffle walls and over the expansion chamber, form a rapidly 85 rising column of hot flame which draws to 90 itself an increasing amount of air which, in the higher portions of the flame becomes intensely heated, thus furnishing the very best conditions for complete combustion.

The apertures 13 are quite small, being 100 of such size that under normal conditions of operation and with the usual pressure of gas supplied for heating and lighting purposes, the gas issues with great force. The apertures are outwardly inclined at 105 such an angle that the pencils of gas strike the baffle walls 14 about on a level with, or a short distance above the center line of the expansion chamber. These pencils of gas striking the two baffle walls are 110 spread out so as to intermingle and are deflected inwardly so that upwardly converg-

ing sheets of flame are produced, which fully unite at some distance above the expansion chamber, in an intensely hot concentrated flame. The converging baffle walls deflect and concentrate the burning gases, increase the upward draft and cause the flames to envelop a large portion of the expansion chamber which is thereby raised to a high temperature. The gas is thus heated and expanded before it issues.

Figure 6 shows a group of burners arranged for use in a heating furnace. A number of burners may be connected in tandem by means of pipe sections 20, so that a portion of the gas entering the first burner, passes on to the other burner or burners connected in line therewith. This arrangement of burners in series gives very satisfactory results. Valves *a*, *b* and *c* control the supply of gas to the several series of burners. It will be seen that by opening one or more of these valves, either two, three, four, five or seven burners may be brought into use, depending on the amount of heat required. The valves also serve to throttle or restrict the flow to any desired extent, so that either a strong or weak flame may be maintained. A valve *d* controls the flow through the main pipe to the manifold 30 21 to which the several series of burners are connected.

In Figure 7, a different arrangement of burners is shown. In this instance, any number of burners from one to five may evidently be used at one time.

A great variety in the arrangement and number of burners used in any group, may be resorted to. Modifications in the construction of the burner itself may also be resorted to within the spirit and scope of my invention.

What I claim as new, and desire to secure by Letters Patent of the United States, is,—

1. A gas burner comprising, in combination, a heating chamber into which the fuel gas is conveyed, means providing outlets below said chamber through which the gas issues in upwardly directed jets for combustion, and means to direct the jets of burning gas in a path adjacent the heating chamber and thereby maintain the latter at a high temperature, said last mentioned means comprising a baffle wall directly in the path of said jets and arranged to deflect the fuel gas toward said chamber and cause it to mix with the air as it strikes said wall.

2. In a gas burner, the combination of a heating chamber into which the fuel gas is directed, means providing outlets for the gas beneath said chamber through which the gas issues in upwardly directed jets, and upwardly and inwardly inclined deflector plates in the path of said jets for directing the issuing gas and causing it to envelop said chamber, whereby the gas in said chamber

is heated to a high temperature before it issues.

3. In a gas burner, the combination of a heating chamber into which the fuel gas is directed, means providing outlets for jets of gas beneath said chamber, and baffle walls on opposite sides of said chamber in the path of said jets and against which the said jets are directed, said walls being arranged to deflect the burning gas inwardly toward the heating chamber.

4. A gas burner comprising a horizontally disposed heating and expansion chamber into which the fuel gas is directed, means providing restricted apertures through which the gas issues at points below said chamber, said apertures being arranged to direct the gas upwardly in jets at opposite sides of said chamber, and baffle walls directly in the path of the upwardly moving jets of gas arranged at such an angle to said walls that the burning gas is deflected inwardly and upwardly on opposite sides of said chamber.

5. A gas burner comprising a horizontally disposed heating and expansion chamber into which the fuel gas is directed, means providing restricted apertures through which the gas issues at points below said chamber, said apertures being upwardly and outwardly inclined and arranged to direct the gas upwardly and outwardly in jets at opposite sides of said chamber, and baffle walls directly in the path of the upwardly and outwardly moving jets of gas arranged at such an angle to said walls that the burning gas is deflected inwardly and upwardly on opposite sides of said chamber.

6. A gas burner comprising a main heating and expansion chamber and lateral extensions thereof at the lower side of said chamber, said extensions having perforations in the walls thereof through which the gas issues in jets at opposite sides of the main chamber, said perforations arranged to direct the issuing jets of gas upward, and inwardly and upwardly inclined deflecting walls in the direct path of said jets and operable to deflect the upwardly moving jets of gas inward and cause them to envelop the major portion of said chamber.

7. A gas burner comprising a main heating and expansion chamber and lateral extensions thereof at the lower side of said chamber, said extensions having perforations in the walls thereof through which the gas issues in jets at opposite sides of the main chamber, said perforations arranged to direct the issuing jets of gas upward, and upwardly and inwardly inclined baffle walls at opposite sides of said chamber directly in the path of the upwardly moving jets of gas.

8. A gas burner comprising a horizontally disposed heating chamber having a pipe

- connection at one end for the entrance of fuel gas and a removable plug at the opposite end permitting a pipe connection whereby a portion of the gas entering said chamber and heated therein may be conducted to another burner or burners, means for directing gas from said chamber and causing it to issue through restricted apertures provided at opposite sides of the chamber, in 10 upwardly directed streams or pencils of gas, and inclined deflector plates directly in the path of said pencils of gas and arranged to confine and direct the flames toward said chamber.
- 15 9. A gas burner comprising a horizontally disposed heating chamber having a pipe connection at one end for the entrance of fuel gas and a removable plug at the opposite end permitting a pipe connection whereby a portion of the gas entering said chamber and heated therein may be conducted to another burner or burners, means for directing gas from said chamber and causing it to issue through restricted apertures provided at opposite sides of the chamber, in 20 upwardly directed streams or pencils of gas, and upwardly and inwardly inclined baffle walls extending lengthwise of said heating chamber on opposite sides thereof, said walls arranged in the direct path of said pencils of gas and operable to spread the gas as it strikes said walls and mix it with the air and also cause the upwardly moving flames to converge and meet above said chamber.
- 25 30 35 10. In a gas burner, in combination, a heating and expansion chamber cast in a

single piece and comprising an approximately cylindrical horizontal body having lateral extensions arranged at intervals along the lower side thereof, said extensions being formed with restricted upwardly directed openings for the issuance of the gas, and baffles positioned above said openings.

11. A gas burner comprising a hollow body providing a heating chamber, said body formed with threaded openings at its ends, a pipe and plug threaded in said openings respectively, a one piece baffle comprising side plates or walls extending lengthwise of said body and end plates to fit over the ends of said body, said body provided with lugs to support the baffle, said end plates being arranged to pass beneath said pipe and plug, whereby the baffle is 50 55 locked to said body.

12. The combination of a container for fuel gas, said container having upwardly directed outlet openings in the walls thereof arranged to permit the gas to issue in jets 60 directed upwardly from said openings, a baffle wall in the path of said jets at an acute angle thereto, said wall being positioned and arranged to form a deflector and mixer for the air and gas whereby an explosive mixture is formed at said wall and burns in a flame extending upwardly from the wall at an acute angle thereto.

Signed at Toledo, in the county of Lucas and State of Ohio, this 6th day of May, 1922. 70

JEROME TRAVIS.
